J. H. BELL,
TELEGRAPH SYSTEM.
APPLICATION FILED JULY 12, 1917.

1,272,191.

Patented July 9, 1918.

UNITED STATES PATENT OFFICE.

JOHN HUME BELL, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEGRAPH SYSTEM.

1,272,191.

Specification of Letters Patent.

Patented July 9, 1918.

Application filed July 12, 1917. Serial No. 120,169.

To all whom it may concern:

Be it known that I, JOHN H. BELL, a citizen of the United States, residing at East Orange, in the county of Essex and State 5 of New Jersey, have invented certain new and useful Improvements in Telegraph Systems, of which the following is a full, clear, concise, and exact description.

This invention relates to telegraph systems, and more particularly to telegraph transmitting apparatus and systems wherein current changes may be readily set up and imparted to a single line conductor all in a manner to permit such currents to be 15 translated into telegraphic code characters, or to be reproduced in a printed form by suitable receiving apparatus at a distant station.

The object of this invention is to provide 20 a telegraph transmitter capable of performing the necessary functions in a reliable and efficient manner to render service of special value in connection with line conductors having low time constant characteristics as 25 in submarine cable working.

In carrying out this invention, electro-responsive switching means are provided for selecting predetermined circuits adapted to affect the potentials of currents supplied 30 from an alternating current source, a distributing means being provided for establishing such prepared circuits effective to control the strength of signaling impulses impressed on a line conductor.

This invention is illustrated diagrammatically in the accompanying drawing in which only so much of a transmitter equipment is shown as will be necessary to a clear understanding of the present invention.

Referring to the drawing, a main line conductor 1 connects, through one winding 3 of a current transformer 2, to an earth connection 5. A bipolar alternating current generator 8 is connected to form a closed 45 circuit through a winding 4 of the transformer 2, and resistance units 9 and 10. A source of direct current supply 14 is provided to act in connection with transmitter initiating contacts 20, 30, 40, 50, 60 and 70 50 for operating respective ones of impulse modifying relays or switching units 22, 32, 42, 52, 62 and 72. A lock-release relay 80 is provided for deenergizing, at a proper moment, any one of the impulse modifying 55 relays which may have been energized in

the setting up of a three-unit code signaling impulse combination. A current distributor or switching unit 90 carries a contactor arm 91, adapted to be rotated by means (not shown) in a counterclockwise direction for 60 sweeping over the segments 94, 95 and 96 in picking up telegraphic impulses and over segment contacts 97 and 99 to control the lock-release relay 80. Conductors 17, 18 and 19, extending in derived circuit relation 65 from the resistance units 9 and 10, are connected to coöperate with the contact members of the impulse modifying relays and the contactor segments of the current distributor 90 in setting up conditions for 70 varying the potentials and strengths of alternating currents which are established through the transformer 2 by the generator 8. Such changes in current strengths in the transformer 2 follow predetermined signal- 75 ing combinations, and as such effect corresponding current changes in the main line conductor 1.

In more specifically describing the operations by which the features of this invention may be practised, let it first be understood that the contacts 20, 30, 40, 50, 60 and 70 are preferably to be arranged and equipped in a manner to permit operation thereof to be controlled by means of a 80 punched or perforated tape, all in a well known manner and as commonly employed with printing telegraphs. The moving parts of the generator 8, current distributor 90, and the forward travel of the perforated 85 tape are to be correlated in such a manner that circuit completion from each one of the segments 94, 95 and 96 of the distributor 90 will be in unison with a one-half cycle or an alternation from the generator 8, and 90 the operation of the lock release relay 80, to deenergize the impulse modifying relays 92, 32, 42, 52, 62 and 72, may take place at the zero current phase angle moment of the current cycles from the alternating current 100 generator 8.

For convenience of description, let it now be assumed that the generator 8, distributor 90, and a perforated transmitting message tape (not shown), are all suitably active to 105 set up and impart to the line conductor 1, three-unit impulse cycles of telegraphic currents. And let it be further assumed that an alternation of incremented maximum current of positive polarity, a minimum cur- 110

rent strength negative alternation, and an incremented mean current strength positive alternation comprise a code selecting cycle corresponding with the letter "I" which will 5 now be considered. The perforated transmitting strip will first effect the closing of contacts 30 and 60, thereby establishing two circuits one of which extends from the grounded current source 14, bus conductor 10 16, contacts 30, conductor 31, winding of the relay 32, conductors 33 and 18, and the contacts 81 of the lock-release relay 80 to an earth connection 82. Through this circuit the relay 32 is initially operated to establish a self-locking path through its contacts 34 and conductor 15 to the source 14. This relay thereby prepares an impulse circuit which may be traced from the bus conductor 19 of the generator 8, conductor 35, 15 contacts 36 of the relay 32 and conductor 37 to the segment 94 of the distributor 90. At the instant the contactor arm 91 arrives at the segment 94, the driving arrangement (not shown) will have moved the armature 20 of the alternating current generator 8 to the zero current phase point following which a positive alternation half-wave of current will be generated and imparted to the bus conductor 19, thence to traverse the circuit, 25 just traced, to the segment 94 of the distributor 90. During the time the contactor arm 91 is passing over the segment 94, it completes a connection by its spanner type brush 92 from this segment to the common 30 contact ring 93 from which the conductor 17 extends to the derived circuit connection at a point between the resistance unit 10 and the winding 4 of the transformer 2. Therefore, it will be apparent that, during the activity 35 of the positive alternation of current from the generator 8, the circuit, just traced through the contacts of the relay 32 and the distributor 90, will effect a shunt path therefor around each one of the resistance units 40 9 and 10, thereby reducing the resistance of the closed generator circuit, permitting the generator to therein develop an incremented current of high or maximum current value. This current acting in the primary winding 45 4 of the transformer 2 sets up a correspondingly characteristic current in the secondary winding 3 of the transformer. Such induced current in the winding 3 of the transformer completes circuit from the earth connection 5 and the main line conductor 1 to an earth connection at a distant receiving station (not shown). For the second current impulse unit of the code for the letter I, no action takes place with respect to 50 the perforated strip controlled contacts or at the distributor 90. During the time the contactor arm 91 of the distributor is passing over the present non-energizing segment 95 (the circuit of this segment now 55 standing open at the contacts 46 and 56 of the relays 42 and 52, respectively), the armature of the generator 8 will be active in generating a negative alternation of current to thereby complete the alternating current cycle started at the instant the arm 91 arrived at the segment 94. Under the negative alternation each one of the resistance units 9 and 10 is fully effective in the closed generator circuit already traced, thereby reducing to a predetermined minimum the 70 strength of this impulse of current through the primary winding 4 of the transformer 2. Accordingly, a correspondingly reduced current wave will be set up in the line circuit 1 by way of the secondary winding 3 75 of the transformer. In setting up and imparting the third or last impulse unit to the line circuit 1, the perforated transmitting tape having already closed the contacts 60 as mentioned, thereby completes a circuit 80 from the current source 14, bus conductor 16, contacts 60, conductor 61, winding of the relay 62, conductors 63 and 13, and contacts 81 of the lock-release relay 80 to the earth connection 82. Energization of the relay 90 62 thereby takes place, and, through its contacts 64 and the bus conductor 15, a self-locking path is established from the current source 14. An impulse circuit prepared by the operation of this relay extends from the 95 generator bus 19, resistance unit 9, bus conductor 18, conductor 65, contact 66 of the relay 62, thence over conductor 67 to the segment 96 of the distributor 90. At the instant the contactor arm 91 arrives at the 100 segment 96 of the distributor 90, the armature of the generator 8 will be just leaving the zero current point of its phase angle to set up an alternation of current having positive polarity with respect to the generator 105 bus conductor 19. During the time the contactor arm 91 is traversing the segment 96, the negative alternation present thereon flows over this arm to the common ring 93, thence over the conductor 17 to the derived 110 circuit point on the closed generator loop already described. From the circuit traced, it will be noted that the contacts 66 of the relay 62 and the distributor 90 establish a shunt path around the resistance unit 10. 115 The resistance unit 9, now being alone in series with the generator 8 and primary winding 4 of the transformer 2, it follows that the current action in this circuit will be incremented to a medium or mean 120 strength with respect to the first two impulse units described. Therefore, through the action of the transformer 2, the secondary winding 3 thereof will impart a current wave of corresponding strength to the line 125 conductor 1. Immediately after passing from the segment 96, the contactor arm 91 of the distributor 90 establishes a connection between the contacts 97 and 99, thereby completing a circuit which may be traced from 130

the current source 14, bus conductor 16, contact 97, brush 98, carried by but insulated from the arm 91, contact 99, conductor 83 and winding of the relay 80 to the earth connection 82. The lock-release relay 80 thereupon responds to separate its contacts 81, thereby disconnecting the selflocked relays 32 and 62, which immediately resume their inert or normal condition. As already mentioned, this operation of the lock-release relay 80 and the resulting deenergizing of any one of the relays 22, 32, 42, 52, 62 and 72, which may have been employed in setting up a transmitted three-unit code of impulses, may take place at a time when the armature of the alternating current generator 8 is at a zero current point of its cycle.

From the foregoing description, it will be apparent that the contacts 24, 34, 44, 54, 64 and 74 serve to establish individual locking circuits for respective ones of the relays 22, 32, 42, 52, 62 and 72, the locking circuit being effective after a relay has initially responded to a momentary closing of its respective one of the contacts 20, 30, 40, 50, 60 and 70. It will also be noted that contacts 26, 46, and 66 of the corresponding relays 22, 42 and 62 establish direct connection from the derived circuit bus conductor 18 to respective ones of the segments 94, 95 and 96 of the distributor 90, thereby shunting out the resistance unit 10 during the time the contactor arm 91 may be active on these segments. And further, that contacts 36, 56 and 76 of corresponding relays 32, 52 and 72 establish a shunt path from the generator bus conductor 19 to respective ones of the segments 94, 95 and 96, thereby short-circuiting both of the resistance units 9 and 10 during the time the contactor arm 91 may be present over either one of these segments.

Directing attention to the three idle segments on the lowermost half of the distributor 90, it will be understood that a second group of relays and controlling contacts therefor, similar to those shown in the drawing, may be interconnected in like manner to these segments, thereby permitting such second transmitter to work to the line conductor 1 in multiplex relation with the transmitter shown. For multiplex working, it will be apparent that, during the time the contactor arm 91 of the distributor 90 is traversing the three lowermost segments,

the perforated transmitting tape may continue active in selecting ones of the relays 22, 32, 42, 52, 62 and 72 for preparing circuit conditions for a next cycle of three-unit code impulses at the segments 94, 95 and 96 and vice versa with respect to action in the equipment for the second transmitter during the time the arm 91 is over the three uppermost segments. In providing equipment for a second transmitter group, it will be understood that an individual lock-release relay would be required therefor and that this relay may be under control of contacts (not shown) but similar to, and located directly opposite, the contacts 97 and 99, which control the present lock-release relay 80.

What is claimed is:

1. In a telegraph system of the class wherein means under the control of relays are employed for varying the strength of half-waves from a source of alternating current to effect signaling, the combination of contacts for selectively preparing in advance of service operative combinations of said relays, and distributor means for establishing operated ones of said relays effective with said means for varying the strength of half-waves of currents from said alternating current source.

2. In a telegraph system, a source of alternating currents, a plurality of relays, a distributor, resistances jointly controlled by said relays and said distributor for affecting the strength of successive alternations from said source of current, and a relay for disabling said first mentioned relays.

3. In a telegraph system, a plurality of relays, a source of alternating currents, a distributor, resistances, transmitter switching means for selectively operating said relays in preparing circuits whereby said resistances may be made effective to control the strength of currents from said current source, a relay for retaining said first mentioned, relays operated, and distributor means to coöperate with the relays in establishing said resistances effective to vary the strength of successive impulses of current from said source.

In witness whereof, I hereunto subscribe my name this 10th day of July A. D., 1917.

JOHN HUME BELL.
